COMBINED KEY RING AND KNIFE

Edward M. Stolarz, New York, N.Y., assignor to The Britton Corporation, Newington, Conn., a corporation of Connecticut

Filed Jan. 3, 1964, Ser. No. 78,065

Term of patent 14 years

(Cl. D22—3)

FIGURE 1 is a top view of a combined key ring and knife showing my new design;

FIGURE 2 is a side elevational view thereof;

FIGURE 3 is a bottom view thereof;

FIGURE 4 is an elevational view of the side opposite to that of FIGURE 2;

FIGURE 5 is a front edge view thereof (adjacent the rivet);

FIGURE 6 is a rear edge view thereof; and

FIGURE 7 is a top view thereof showing an implement in extended position in partial phantom line.

The essential features of my design reside in the portions shown in full line.

Portions of the broken line showing of the key ring and chain have been omitted from FIGURES 2-6 for convenience of illustration.

I claim:

The ornamental design for a combined key ring and knife, as shown and described.
